CLAIM

The ornamental design for a pump assembly for a toilet, as shown and described.

DESCRIPTION

FIG. 1 is a perspective view of a pump assembly for a toilet showing our new design in operative associated with a pump assembly;

FIG. 2 is a front view of the pump assembly for a toilet of FIG. 1;

FIG. 3 is a left side view thereof;

FIG. 4 is a right side view thereof;

FIG. 5 is a top view thereof; and,

FIG. 6 is a rear view thereof.

The broken line showing of a toilet bowl is included for the purpose of illustrating toilet pump and forms no part of the claimed design.
